UNITED STATES PATENT OFFICE.

BERT O. TILDEN, OF TRENTON, NEW JERSEY, ASSIGNOR TO B. O. T. MFG. CO., OF TRENTON, NEW JERSEY, A CORPORATION OF NEW JERSEY.

DESIGN FOR COMBINED FLUSH TANK AND CABINET.

Application filed May 4, 1928. Serial No. 26,563. Term of patent 14 years.

To all whom it may concern:

Be it known that I, BERT O. TILDEN, a citizen of the United States, residing at Trenton, in the county of Mercer and State of New Jersey, have invented a new, original, and ornamental Design for Combined Flush Tank and Cabinet, of which the following is a specification, reference being had to the accompanying drawing, forming a part thereof.

Figures 1, 2 and 3 are respectively a front elevation, an end elevation, and a top-plan of the combined flush tank and cabinet showing my new design.

I claim:

The ornamental design for combined flush-tank and cabinet, as shown.

BERT O. TILDEN.
